CLAIM

I claim the ornamental design for a plunger pot, as shown.

DESCRIPTION

FIG. 1 is a perspective view of a plunger pot showing my design;

FIG. 2 is a front side elevational view thereof;

FIG. 3 is a right side elevational view thereof, the left side being a mirror image thereof; and,

FIG. 4 is a rear side elevational view thereof.

1 Claim, 4 Drawing Sheets**FIG. 1**

FIG. 2

FIG. 3

FIG. 4
